UNITED STATES PATENT OFFICE.

THOMAS B. ATTERBURY, OF PITTSBURG, PENNSYLVANIA.

DESIGN FOR A DISH-COVER.

SPECIFICATION forming part of Design No. 19,282, dated August 27, 1889.

Application filed July 29, 1889. Serial No. 319,088. Term of patent 7 years.

To all whom it may concern:

Be it known that I, THOMAS B. ATTERBURY, a citizen of the United States, residing at Pittsburg, in the county of Allegheny and State of Pennsylvania, have invented and produced a new and original Design for Dish-Covers; and I do hereby declare the following to be a full, clear, and exact description of the same, reference being had to the accompanying drawing, forming a part thereof.

In the drawing I have shown a dish-cover in side elevation, in general form that of an oblong plinth with corners slightly rounded, and having the figure of a cat encouchant formed thereon and covering the top portion of the same. The base portion or cover proper is of rectangular form with rounded corners, the sides of which are inclined from the bottom inward and are curved outward. The top portion of the base has a slightly-raised portion, which corresponds to the outline of the bottom of the cover, though somewhat smaller. Upon this raised oblong portion and nearly covering the same is the configuration of a cat lying down.

Referring to the drawing by letter, A indicates the base or pedestal, which is rectangular in general form with corners and sides rounded and inclining inward from the bottom.

The letter a indicates the slightly-raised oblong portion, which has its corners round, and on which the figure of a cat lying down, as on a mat, is formed, said figure of a cat having its head erect and turned to one side, 35 constituting the handle portion B of the cover.

What I claim is—

A design for a dish-cover, consisting of the oblong base portion A, with its corners and sides curved outward and inclined inward 40 from the bottom to the top portion, and having a slightly-raised oblong portion a, with round corners, and the figure of a cat formed thereon, substantially as shown.

In testimony whereof I affix my signature in 45 presence of two witnesses.

THOMAS B. ATTERBURY.
